(57) **CLAIM**

The ornamental design for a toy figure as shown and described.

DESCRIPTION

FIG. 1 is a front view of a toy figure of the present invention.

FIG. 2 is a rear view thereof.

FIG. 3 is a left view thereof.

FIG. 4 is a right view thereof.

FIG. 5 is a top view thereof.

FIG. 6 is a bottom view thereof.

FIG. 7 is a first perspective view thereof.

FIG. 8 is a second perspective view thereof.

FIG. 9 is a third perspective view thereof.

FIG. 10 is a fourth perspective view thereof; and,

FIG. 11 is a fifth perspective view thereof.

The broken line showing of the toy figure is for the purpose of illustrating portions of the article that forms no part of the claimed design.
